UNITED STATES PATENT OFFICE.

CHARLES F. MOORE, OF CAMBRIDGE, MASSACHUSETTS.

ADJUSTABLE CONCRETE FORM.

Application filed September 18, 1920. Serial No. 411,092.

To all whom it may concern:

Be it known that I, CHARLES F. MOORE, a citizen of the United States, residing at Cambridge, in the county of Middlesex and 5 State of Massachusetts, have invented certain Improvements in an Adjustable Concrete Form, of which the following description, in connection with the accompanying drawings, is a specification, like reference 10 characters on the drawings indicating like parts in the several figures.

This invention relates to forms used to support a concrete column while the concrete is poured and subsequently during the 15 period required for the concrete to set sufficiently to become self-sustaining.

As is well understood by those skilled in this art, it is now the usual practice to make the forms required for this purpose 20 out of lumber. This practice is recognized as expensive both in labor and materials. That is, skilled labor is required in setting up forms of this character, and while a certain part of the lumber from which these 25 forms are made can usually be employed in the manufacture of other forms, still the waste is very large. A further disadvantage of this practice is that after the forms have been removed from the column the ridges 30 and inequalities in the surfaces caused by the variations in the thickness of the boards, and by the joints between the boards, must be dressed down and this dressing or finishing operation also requires much labor.

With a view to reducing the expense in making concrete columns of this character it has been proposed heretofore to use sheet metal forms and such forms have been used with considerable success in making 40 columns of circular cross section. Such forms, however, have never been successfully employed, so far as I have been able to learn, in the making of columns of rectangular cross section or other polygonal cross 45 sectional shapes. It is the chief object of the present invention to devise a form of this character which shall be adjustable for a great variety of cross sectional dimensions of a given cross sectional shape and with 50 the aid of which the expense for labor and materials in constructing forms of this character can be greatly reduced.

The nature of the invention will be readily understood from the following description 55 when read in connection with the accompanying drawings and the novel features

will be particularly pointed out in the appended claims.

The invention will be herein disclosed as embodied in a form designed especially for 60 the construction of columns of rectangular cross section, although it will be readily appreciated that the invention is equally applicable to forms for columns of other polygonal cross sections. 65

Referring now to the drawings,

Figure 1 is a horizontal cross sectional view through a column supported by an adjustable form constructed in accordance with the present invention; 70

Fig. 2 is a side elevation of the construction shown in Fig. 1;

Fig. 3 is an elevation of the right side of the form shown in Fig. 1, a part of this figure being broken away better to illustrate 75 the details of the construction;

Fig. 4 is a cross sectional view on the line 4—4, Fig. 3, looking upwardly; and

Fig. 5 is a cross sectional view on the line 5—5, Fig. 1. 80

The form shown comprises four sections arranged in two pairs, the members of each pair being duplicates of the corresponding members of the other pair. Each section supports one corner of the column and the 85 sections are designated at A, B, C and D, respectively. Section A comprises two plates *a* and *a'* which lie at right angles to each other and are secured rigidly together at their adjacent edges by being riveted to 90 an angular strip 2. These two plates define one corner of the column, it being understood that the edge formed by the intersection of two faces of a column is commonly referred to as a "corner." Each of 95 the other sections includes similar plates secured together in a like manner, the plates of the section B being designated at *b* and *b'*, those of section C at *c* and *c'*, and those of section D at *d* and *d'*, respectively. Each 100 pair of plates defines one corner of the column, and the corresponding plates of similar pairs are supported in overlapping relationship and support the four vertical faces of the column. Each plate preferably consists of sheet metal of suitable thickness. It 105 is contemplated that rolled steel or iron plates, galvanized if desired, will be used and each plate for most purposes need not be over one-sixteenth of an inch in thickness.

For the purpose of supporting these plates

in their operative positions, each of the sections above mentioned includes truss-like frame members which are secured together to encircle the plates, and several of these 5 encircling frames are provided on each form, the several frames being spaced apart vertically of the form at the required intervals to give the necessary rigidity to the frame and prevent the plates from buckling.

- 10 The frame for the section A comprises two parallel metallic bars 3 and 4 of angular cross section spaced apart but secured rigidly together by cross pieces 5, 6 and 7, and if desired also by diagonal members. 15 The frame part formed by these members lies parallel to the plate *a* and supports this plate. This frame section also includes three other members or bars lying parallel to the plate *a'*, these members being designated at 20 8, 9 and 10, respectively, and the two latter members being of angular cross section. Cross pieces 11, 12 and 13 riveted to these parts secure them in the desired spaced relationship, and the downwardly projecting webs of the angular pieces 4 and 13 are secured together by bolts 15—15, Fig. 4.

For the purpose of securing this section to the corner plates *a* and *a'*, the plate *a*, and the corner angle piece 2 where these 30 parts project beyond the plate *a'*, have a hole punched therein to receive a lug or extension 16 of the member 6, and a tapered key or wedge 17 is driven through the slot in this tongue and cooperates with the face of 35 the part 2 to secure this frame section firmly to the plates *a* and *a'*.

For the purpose of further bracing the corners, the downwardly projecting flanges of the members 3 and 4 are riveted to the 40 ends of a rod 18 and a curved rod 19 has its ends riveted respectively to the cross piece 11 and to the flange of the cross piece 13, this construction being best illustrated in Fig. 4.

45 The corresponding part of the section B includes the same frame members as that of the section A, but these members are reversed and accordingly the parts of this frame section are designated by the same numerals as those used for the corresponding parts of section A except that these numerals are primed. The section C is an exact duplicate of the section A, while the section D is a duplicate of the section B.

55 The sections are adjustably secured together in a manner which enables them to be set up relatively to each other in various relationships depending upon the desired cross sectional dimensions of the column to be made. For this purpose the angle members 3 and 4 of the section A overlap the corresponding members 3' and 4' of the section D and these members are secured together 60 by bolts 20, 21 and 22 which enter holes formed in these parts. It will be seen that

each of the parts 3, 3' 4 and 4' are provided with a series of holes spaced apart at regular intervals so that a great range of adjustment is provided for the sections A and D toward and from each other.

The sections A and B are similarly connected together by bolts 24. That is, the parts 8 and 8', 9 and 9', 10 and 10' overlap and are provided with holes spaced similarly to those in the parts 3, 3' and 4', and the bolts 24 secure these parts together, this construction providing for a variation in the distance between the sections A and B similar to that provided between the sections A and D. The same provision is made for 80 securing the section C to the sections B and D.

The overlapping edges of the four pairs of plates also are preferably secured directly together by bolts, the plates having a series 85 of holes 25, Fig. 3, formed therein to receive bolts 26 the heads of which are counter-sunk into the inner surface of the plate *b*. A similar arrangement is provided for securing each pair of plates together and these connections are spaced apart vertically of the form by the same intervals that space the frames apart vertically.

It will now be appreciated that when this form has been set up in the location in 95 which a column is to be made the column can be poured in the usual manner, and when the column has set sufficiently to be self-sustaining the form can then be removed simply by removing from each frame the 100 bolts that secure the four sections together, and the bolts that also secure the overlapping plates together.

When this form is to be set up again it is merely necessary to assemble the sections 105 in the general relationship shown in Fig. 1 and bolt together the frame sections A, B, C and D of each frame, these sections being adjusted relatively to each other prior to the bolting operation to cause the plates 110 to enclose a space of the cross sectional dimensions required for the column. The overlapping plates may be secured together by the bolts 26 either before or after the frame sections are secured together. For 115 small columns it will not be necessary to have the encircling frames at as frequent vertical intervals as will be required for large sections, and a greater or smaller number of these frames may be used as desired. It 120 will be evident, however, that this construction reduces very substantially the labor required to set up a form preparatory to pouring the column and that it also reduces the labor required to take down the form 125 after the column has set. Furthermore, the depreciation on a metallic form of this character is very small when compared to the depreciation of wooden forms. A further advantage of this construction is that 130

the surfaces of the finished column require relatively little dressing or finishing, the only seams being those formed by the overlapping plates, and these seams are much 5 smaller and very much fewer in number than those formed by the present practices.

While I have herein shown and described the best embodiment of the invention of which I am at present aware, it will readily 10 be understood by those skilled in this art that this embodiment may be modified in many particulars without departing from the spirit or scope of this invention.

What is claimed as new is:

15 1. An adjustable form for concrete columns of rectangular cross section, comprising four pairs of plates, means for securing each pair together in a right angular relationship to each other to support one 20 corner of a column, and four angular frame sections, one for each of said corners, each section being secured to its respective pair of plates, and means for adjustably securing said sections together to support the plates 25 in position to enclose the space in which a concrete column is to be poured with said frame encircling the plates.

2. An adjustable form for concrete columns of polygonal cross section comprising a plurality of plates for supporting the vertical faces of a column, a truss-like frame supporting said plates and adjustable to 30 vary the cross sectional dimensions of the space enclosed by said plates, said frame 35 comprising a plurality of truss sections each

including a pair of parallel bars spaced apart, and members rigidly connecting said bars together.

3. An adjustable form for concrete columns of polygonal cross sections comprising a plurality of plates for supporting the vertical faces of a column, a truss-like frame supporting said plates and adjustable to 40 vary the cross sectional dimensions of the space enclosed by said plates, said frame 45 comprising a plurality of truss sections each including a pair of parallel bars of angular cross section spaced apart, and members securing said bars rigidly together.

4. An adjustable form for concrete columns of polygonal cross section comprising, in combination, a pair of plates secured rigidly together and defining each corner of a column, and a truss-like frame supporting a plurality of said pairs of plates 50 in position to constitute a closed form for a column, the adjacent plates of each pair overlapping and serving to form the supporting surface for the respective vertical faces of the column, said frame comprising 55 truss corner sections having overlapping parts adjustably secured together to vary the amount of overlap of said plates while maintaining said corner plates in a constant relationship to each other, whereby 60 the cross sectional dimensions of the column enclosed by the plates may be varied.

In testimony whereof I have signed my name to this specification.

CHARLES F. MOORE.
